CLAIM

The ornamental design for a ski form, as shown and described.

DESCRIPTION

FIG. 1 is, in front elevation view, the ski form according to the present invention.

FIG. 2 is, in rear elevation view, the ski form of FIG. 1.

FIG. 3 is, a right side elevation view of the ski form of FIG. 1, shown at a larger scale, the left side elevation view being the mirror image thereof.

FIG. 4 is, in bottom elevation view, the ski form of FIG. 1.

FIG. 5 is, in plan view, the ski form of FIG. 1; and,

FIG. 6 is, in front perspective view, the ski form of FIG. 1.

1 Claim, 6 Drawing Sheets

FIG. 1

FIG. 2

FIG. 3

FIG. 4

FIG. 5

FIG. 6
